CLAIM

The ornamental design for a cake mold, as shown and described.

DESCRIPTION

FIG. 1 is a perspective view of the cake mold of my new design showing parts separated.

FIG. 2 is another perspective view thereof.

FIG. 3 is a top plan view thereof.

FIG. 4 is a bottom plan view thereof.

FIG. 5 is an elevational view of one side thereof. The view from the opposite side is a mirror image thereof; and, FIG. 6 is an elevational view of the front thereof. The view from the back is a mirror image thereof.
